US00D421720S

United States Patent

[19]

Eberle et al.

[11] Patent Number: Des. 421,720

[45] Date of Patent: ** Mar. 21, 2000

[54] CONTAINER

[75] Inventors: **Theodore F. Eberle**, Chicago; **Jizu J. Cheng**, Burr Ridge; **Richard G. Kraft**, Joliet, all of Ill.; **Charles M. Brandt**, Lithia Springs, Ga.

[73] Assignee: **Crown Cork & Seal Technologies Corporation**, Alsip, Ill.

[**] Term: 14 Years

[21] Appl. No.: 29/087,361

[22] Filed: May 1, 1998

[51] LOC (6) Cl. 09-01

[52] U.S. Cl. D9/500; D9/434; D9/502; D9/538

[58] Field of Search D9/500, 502, 503, D9/538-540, 545, 557, 434, 559; 215/370-384
